UNITED STATES PATENT OFFICE.

JOHN C. BARCLAY, OF NEW YORK, N. Y.

PERFORATOR.

No. 677,823.

Specification of Letters Patent.

Patented Jan. 28, 1908.

Application filed July 22, 1907. Serial No. 385,000.

To all whom it may concern:

Be it known that I, JOHN C. BARCLAY, a citizen of the United States, residing at New York, in the county of New York and State 5 of New York, have invented certain new and useful Improvements in Perforators; and I do hereby declare the following to be a full, clear, and exact description of the same, such as will enable others skilled in 10 the art to which it appertains to make and use the same.

My invention relates to improvements in perforating machines, and more particularly to machines of the class employed for perforating or otherwise marking paper strips or ribbons, such for example, as those used in the Wheatstone automatic telegraph system and various other automatic printing telegraph systems.

20 My present invention comprises improvements upon the clutch mechanism and paper feed mechanism of the machine set forth in my application for Letters Patent filed December 29th, 1906, Sr. No. 349,967.

25 The objects of my invention are to prevent repeating of characters due to failure of the clutch mechanism to work properly, and to simplify the feeding mechanism of machines such as illustrated and described 30 in my said former application.

The machine described in my said former application, and illustrated herein, in so far as is required for explanation of the present invention, is adapted for perforating paper 35 strips or ribbons for the Wheatstone and similar automatic telegraph systems, and comprises (a) punching mechanism; (b) paper feed mechanism; (c) a key board comprising finger keys and selecting means 40 operated thereby and controlling appropriate devices for the punching and paper feed mechanisms, whereby at each operation of a finger key, the proper combination is "set up" to punch this character in the strip, and by which space determining means are operated to regulate the feeding of the paper strip to correspond with the space occupied by each character so punched; (d) power 45 mechanism independent of but controlled by the keys, whereby the actual work of feeding the paper and of punching is performed by a motor, preferably a continuously running motor.

I will now proceed to describe my invention with reference to the accompanying

drawings and will then point out the novel features in claims.

In the said drawings: Figure 1 shows a top view of my said perforating machine, the box containing the paper reel being 60 shown partly open; Fig. 2 shows a front elevation of the machine; Fig. 3 shows a detail side view of the key board mechanism; the frame of the key board, the selecting bars, and certain other parts being sectioned; 65 Fig. 4 shows a top view and partial horizontal section of the main portions of the punching and paper feed mechanism; Fig. 5 is a detail top view of a portion of the paper feeding device; and Fig. 6 is a detail face 70 view of a portion of the paper feeding device. Fig. 7 is a detail rear view and partial section of the paper feeding mechanism; and Fig. 7^a shows in detail parts of the stop-pin adjusting mechanism. Fig. 8 shows a top 75 view of the gearing and clutches through which the punching and paper feed mechanisms are driven; Fig. 9 shows a front elevation of such gearing and clutches and Fig. 10 shows a detail top view of the clutch through 80 which the punching mechanism is driven. Figs. 11 and 12 are respectively a detail side view and a detail end view of an alternative construction of a part of this clutch releasing device. Figs. 13 and 14 are respectively a 85 transverse section and an axial section of the frictional driving device of the feeding mechanism. Fig. 15 is a detail perspective view of the clutch-opening cam 73.

In the following description I will use so 90 far as practicable the same reference numerals as are applied to the corresponding parts shown in the drawings of my said prior application Sr. No. 349, 967.

In said drawings, 1 designates generally 95 a key board, 2 designates generally a punching mechanism, 3 designates generally paper feed and spacing mechanism, 4 designates a driving motor and 5 designates generally transmission mechanism. The key board 100 comprises finger keys 6 and corresponding key levers 7, each operating, through suitable selecting lugs hereinafter mentioned, certain of two series of selecting bars, 8 and 9, located beneath the key board. These bars are mounted upon pivoted links 10 (Figs. 2 and 7) so as to be capable of moving freely 105 up and down while remaining horizontal at all times; and springs 11 counterbalance the weight of these bars and links and tend to 110

hold the same upward. The bars of series 8 control and, when operated, effect the adjustment of, certain pins of the paper feed and spacing mechanism 3, whereby the distance the paper strip is to be fed is regulated. The bars of series 9 control, and when operated, effect the operation of, certain punch-selecting devices of the punch mechanism 2, whereby appropriate combinations of punches are selected and operated. For depressing the appropriate selecting bars of series 8 and 9, each key lever is provided with one or more lugs 12 (Fig. 3), located over the particular bars of series 9 which that lever is to operate, and is further provided with a similar lug 13 located over the particular bar of series 8 which that lever is to operate. For operating the clutch mechanism hereinafter described by which the power driven member of the punching mechanism and mechanism for adjusting and restoring stops of the paper feed mechanism are operated, I have provided in the machine shown in these drawings, a universal bar 14 located beneath and at right angles to the selecting bars 8 and 9; and, like said bars, mounted upon parallel links 10, and this bar is provided with a hooked extension 15 arranged to engage a transverse trip-operating bar 16 (Figs. 3, 8 and 9) arranged transversely with respect to the key levers and, like selecting bars 8 and 9 and universal bar 14, mounted upon pivoted parallel links 10. It will be observed that when any one or more of the selecting bars of series 9 are depressed the universal bar 14 will be depressed and will in turn depress bar 16, arranged at right angles thereto, such bar being thereby caused to move longitudinally of itself or to the left of Figs. 8 and 9, as will be seen by comparing said figures.

The punching mechanism 3 and certain devices for setting certain stop pins of the paper feed mechanism by which the distance of the paper strip is fed forward is controlled, are operated by a shaft 45 deriving motion, through a suitable clutch 58 and suitable gearing 60, from the motor 4. Said clutch comprises two jaw members, one, 59, driven by the gearing 60, the other, 61, mounted to slide on shaft 45 and having a spring 62 tending to press it into engagement with member 59. A stop 63 (Figs. 8 and 9) pivoted at 64, normally engages a lug 65 carried by this clutch member 61 and holds it out of engagement with clutch member 59, but when universal bar 14 is depressed by the depression of a finger key and causes bar 16 to move to the left of Figs. 8 and 9, a hook 67 connected to said bar 16 and normally in engagement with a trip 68 itself normally in engagement with one end of stop 63, drags said trip 68 out of engagement with stop 63, thus permitting the spring 72 of said stop to pull it upward, so freeing lug 65, and permitting clutch member 61 to be forced by spring 62

into engagement with clutch member 59, thereby causing shaft 45 to revolve. As the left end (as seen in Fig. 9) of stop 63 encounters hook 67 it depresses said hook, so as to cause it to release the trip 68, thereby permitting the spring 71 of said trip to draw it back into position to engage again the stop 63. On shaft 45 is a cam 66 which, as soon as said shaft begins to revolve, engages a bell crank extension 631 of stop 63, and thereby positively forces said stop back into position to arrest the lug 65 of the clutch member 61, at the conclusion of one revolution of shaft 45; and as soon as stop 63 is so moved back to position to arrest lug 65, the trip 68, previously released from hook 67, as above described, engages said stop 63 and holds it in such position. In the path of rotation of lug 65 is a spiral throw-out cam 73 which, near the conclusion of one revolution of the lug 65, engages the same and forces it gradually away from clutch member 59, thus opening the clutch; and at the conclusion of one revolution lug 65 jumps from the end of the cam 73 into engagement with stop 63 and is held thereby.

The construction of the parts is such, it will be seen, that for each depression of a finger key and consequent release of stop 63, only one revolution of the cam shaft 45 can occur. It is important that only one revolution of such shaft shall occur for each depression of a finger key, because a second rotation of the shaft will cause a repetition of the operation of the punching mechanism. Heretofore difficulty has been experienced in devising a reliable clutch and tripping mechanism; some forms of tripping devices producing so much frictional drag on the clutch member 61 as to occasionally prevent prompt engagement of the clutch members when the trip 63 is first operated, and some forms of tripping device failing to return the stop 63 promptly enough to arrest the lug 65 at the conclusion of one revolution. In the mechanism above described, however, the stop 63 is returned positively to arresting position, by engagement of the cam 66 with the bell crank extension 631, almost immediately after shaft 45 has begun to rotate; and said cam holds the stop 63 in such position until ample time has elapsed for the release of trip 68 and the reengagement of the stop 63 thereby. But notwithstanding the positive action of the cam 66 as described, there is no friction whatever between said cam and the bell crank extension 631 at the time when the clutch member 61 is first released, such bell crank extension 631 being then opposite the flattened portion of cam 66 and therefore not then in engagement with said cam. Such bell crank extension 631 is provided with a friction roller 632 to avoid wear between such extension and the cam.

In Figs. 11 and 12 I illustrate an alter-

native device for returning the stop 63 positively. In this form said stop is provided with a cam extension 633 adapted to be engaged by the lug 65. When stop 63 is first released by the action of stop 68, as previously described, and is drawn upward by its spring 72, the cam extension 633 is raised into such position that, as the lug 65 revolves, such extension will be engaged by such lug and depressed thereby, so returning stop 63 to its arresting position. In this form of the device a stop screw 634 is provided to regulate the rise of stop 63, so that the cam extension 633 may not be in engagement with the clutch member 61 at the instant when said member is moving into engagement with clutch member 59.

From the above it will appear that in both forms of the devices illustrated I have provided positive means for returning the stop to its arresting position immediately after the shaft 45 begins to rotate, and for holding the stop in such position until ample time has elapsed for the return of the trip 68 to position to engage and hold said stop; likewise that I have avoided any friction of the stop against the clutch member 61 tending to retard movement of said clutch member into engagement with its companion clutch member 59.

A further feature of my invention relates to means for operating the restoring arm and other parts of the paper feed mechanism. For the understanding of such improvement I will describe briefly the said feeding mechanism.

The paper strip, 22, is drawn from a reel and passes over guide rollers 23, and between retarding tension and guide rollers 24 and 25, and through the punch head 30 between the die plate 31 thereof and the punches 27 of said punch head and thence around toothed wheel 78 provided with teeth 79 and a large number of stop pins 80 arranged to slide vertically in said wheel and surrounded by spiral springs 81 which act as frictional drags to hold said pins in any position in which they may be set against the influence of gravity or vibration. This wheel is rotated intermittently to feed the paper forward between the punching operations, and rotates different distances according to the space occupied on the strip by the character to be punched. This distance is determined by raising different of the stop pins according to the distance the wheel is to be permitted to rotate; each pin so elevated being brought, by the rotation of the wheel, against a shoulder 89 on a plate 82 located immediately above said wheel. When a pin so contacts with said shoulder the motion of the feed wheel is arrested until said pin is depressed (by means to be described presently) and another pin elevated to regulate

the distance the paper is fed forward for the next character.

The appropriate stop pin 80 is elevated by means of one or another of the arms 101 actuated through connecting mechanism by one or another of the selecting bars 8 beneath the key levers 7. Each key lever is provided with a projection 13 (Fig. 3) located so that when said lever is depressed one or another of the bars 8 will be depressed; such projection being located over the particular bar 8 corresponding to the distance the paper strip should be fed forward for the particular character corresponding to that key. Each bar 8 when so depressed operates a pivoted arm 103 (Fig. 7) and, therethrough, the corresponding arm 88. The front ends of these arms 88 are immediately above a reciprocating driver 104; but said arms 88 have in their front ends notches 106 which prevent said driver 104 from raising any one of said arms 88 unless that arm has been pushed forward, as it will be if its corresponding selector bar 8 has been depressed as just described. Above the arms 88 are pivoted pushers 101 arranged transversely with respect to arms 88, the ends of said pushers being beneath the row of stop pins 80 of the said wheel 78. Each pusher has, over the particular arm 88 which is to operate it, a lug 101* (Fig. 7*) deep enough to cause said pusher to be operated by that particular arm 88, but by no other. The several lugs 101* grow progressively deeper from the pivots of the pushers outward, so that the pushers are all raised the same distance notwithstanding the different distances of the several lugs 101* from the pivots of said pushers.

The reciprocating driver 104 is raised each time the shaft 45 revolves by a cam 93 on said shaft and a follower 95 transmitting motion to said reciprocating driver 104, through a spring 105. The actual work of raising the stop pins 80 is performed; therefore, by the power driven shaft 45 and the parts operated by the cam 93 thereon; and the only work done by the key levers, so far as the raising of these stop pins 80 is concerned, is, the moving of an appropriate arm 88 into position to be engaged by the reciprocating driver 104.

After the stopping of the feed wheel 78 by engagement of one of the stop pins 80 with the shoulder 89 of plate 82, and after the punching of the corresponding character in the paper by the action of the punching mechanism, said pin 80 is depressed to normal position and said wheel is permitted to rotate onward until again arrested in the same manner by encounter of another pin 80 with said shoulder 89. The depression of the pins 80 is effected by a restoring arm 90 carried upon a vertically movable rod 91 (Fig. 7), said arm 90 having also some slight pivotal movement

in a horizontal plane and being normally held as far to the left of Fig. 1, by a spring 92, as a slot 84 in plate 82 will permit; in which position it is directly over the end of that stop 5 pin 80 which at the time is in engagement with shoulder 89. Rod 94 is arranged to be raised and lowered by the same cam 93 and follower 95 which operate the reciprocating driver 104; and the shape of the cam 93 is 10 such that after the punching of a character in the strip (which punching is effected by the action of cam 44 on shaft 45 and its follower 42 on the punches within punch head 30, immediately shaft 45 begins to rotate) the follower 15 95 raises rod 91, the arm 90 being drawn to the right (of Fig. 7) by spring 92 as soon as said arm 90 clears the top of the stop pin 80 then in engagement with shoulder 89; the end of arm 90 being thus brought directly 20 over the top of such pin 80. Near the end of the revolution of shaft 45 cam 93 permits follower 95 and rod 91 to descend, so pushing down said pin 80 and permitting the feed wheel to rotate until arrested by engagement 25 of another pin 80 previously elevated with said shoulder 89. As shown particularly in Fig. 5, the end of arm 90 just clears shoulder 89, and each pin 80 when in engagement with said shoulder rests partly against the shoulder and partly against the end of 30 said arm; for which reason it is clear that when said arm is raised above the level of such pin 80 as it will be when rod 91 is elevated by follower 95, it will spring over the top 35 of such pin 80 ready to depress the same when rod 91 descends again. In order that feed wheel 78 may rotate in this intermittent manner, said wheel is driven through a yielding driving device. Said wheel is mounted 40 on a vertical shaft 107 (Fig. 7) driven by spiral gearing 108 from a shaft 109 itself driven from the motor 4 by a gear 110 mounted on said shaft 109 and in frictional driving connection therewith through a spiral spring 45 113 (Figs. 13 and 14) connected at one end to a plate 114 and provided at the other end with a friction cushion 115 rubbing against the inner surface of the rim of said gear 110; said plate 114 carrying one member of a jaw 50 clutch 111, the other member of which is arranged to drive said shaft 109, but is mounted to be moved longitudinally thereon by means of a key 112. This clutch and key are provided to permit unclutching of the feed 55 wheel 78 from the driving motor to facilitate threading of the paper strip through the machine. A pin 117 carried by said key is arranged to be thrust thereby through one of a series of holes 116 in disk 114 whenever said 60 key is operated to open clutch 111; the disk 114 being thereby locked so as to prevent uncoiling of the spiral spring 113.

The operation of this machine is as follows: The motor 4 being in rotation, when 65 one of the finger keys 6 is depressed, a cor-

responding combination of selecting bars 9 is depressed, also that selecting bar of series 8 which will cause the paper strip to be fed forward the distance corresponding to the space occupied by the character of such key. 70 Those bars of series 9 which are so depressed operate corresponding fingers 32 and 33 (Fig. 2) so as to bring them opposite the ends of the corresponding punches in punch head 30 and at the same time universal bar 14 beneath said bars 9, being depressed, depresses bar 16 and so causes it to be moved to the left of Figs. 8 and 9, so pulling out trip 68 and causing stop 63 to release lug 65 of clutch 58 and permit said clutch to close. 75 Rotation of shaft 45 then begins and cam 44 or said shaft operates its follower 42 and causes said follower to operate the selected punches and so punch in the paper strip 22 the holes corresponding to the particular character of the finger key 6 which has been depressed. I do not herein illustrate and describe particularly the arrangement of the punches and punch selecting devices, as these parts are not directly involved in the present invention. The punches of punch head 30 having been operated and having retired again, and cam 93 having meanwhile raised rod 91 so as to cause arm 90 to spring over the top of that stop pin 80 which is at 80 the time holding feed wheel 78 stationary, said cam 93 then permits follower 95 and rod 91 and arm 90 to descend, so depressing that pin 80 which has been holding wheel 78 stationary and permitting wheel 78 to rotate, 100 so feeding the paper forward. At the instant when the particular finger key 6 operated depressed the appropriate bars of series 9 as above stated, the particular bar of series 8 also depressed as above stated, caused its 105 corresponding arm 88 to move out over the end of the reciprocating driver 104 (Fig. 7); and when cam 93 caused rod 91 to rise it also raised driver 104, thus elevating another of pins 80. This all takes place before the depression of that pin 80 which has been holding the wheel 78 stationary, as above described. Wheel 78 now rotating, that pin 80 which has just been raised by the action of the finger key 6, arrests said wheel 78 110 115 when such pin 80 comes in contact with stop shoulder 89. A cycle of operation has not been completed, the wheel 78 has fed the paper forward a distance corresponding to the space on said strip occupied by the character just punched, and the machine is in readiness for the depression of the same or any other finger key 6 and for the commencement of a new cycle. At the instant when bar 16 was pulled to the left as above described, and stop 63 caused to release the clutch member 61, friction roller 632 was opposite the flattened portion of cam 66 and so not in engagement with said cam, therefore offering no resistance to the movement 120 125 130

of clutch member 61 into engagement with clutch member 58. When shaft 45 is rotated a few degrees, however, cam 66 engages said friction roller 631 and moves stop 63 positively into position to arrest the lug 65 at the completion of one revolution of the shaft 45. Trip 68 having previously been released from hook 67, holds stop 63 in such position. The paper strip after passing the feed wheel 78 is led out through a guide 26, passing across and above the key board, that face of said guide which is toward the key board being open so that the operator may read the message punched.

15 What I claim is:—

1. A machine of the class described comprising in combination punching and paper feed mechanism, character members and selecting means operated thereby controlling the same, a power member, a clutch, and releasing means therefor comprising a stop for the clutch, means for operating the same to release the clutch and positive returning means for said stop operated by said power member to move said stop back to arresting position.

2. A machine of the class described comprising in combination punching and paper feed mechanism, character members and selecting means operated thereby controlling the same, a power member, a clutch, and releasing means therefor comprising a stop for the clutch, means for operating the same to release the clutch and a cam arranged to positively return said stop to arresting position.

3. A machine of the class described comprising in combination punching and paper feed mechanism, character members and selecting means operated thereby, controlling the same, a power member, a clutch comprising a sliding member, clutch releasing means comprising a stop normally engaging said sliding member and holding the clutch open, means for operating the stop to permit the clutch to close, and a cam arranged to move said stop into arresting position, said cam normally out of engagement with said stop.

4. A machine of the class described comprising in combination punching and paper feed mechanism, character members and se-

lecting means operated thereby controlling the same, a power member, a clutch comprising a sliding member, clutch releasing means comprising a stop normally engaging said sliding member and holding the clutch open, means for operating the stop to permit the clutch to close, said stop having a bell crank extension and a cam mounted to rotate with said clutch and adapted to engage said bell crank extension to positively restore the stop to arresting position, said cam having a flattened side normally opposite said extension.

5. A machine of the class described comprising in combination punching and paper feed mechanism, character members and selecting means operated thereby controlling the same, a power member, a clutch, a stop normally holding said clutch open and tripping means for said stop comprising a universal member arranged to be operated by the finger keys, a hook operated thereby and a trip normally engaged by said hook and normally engaging said stop, the stop arranged when operated to disengage said hook from said trip.

6. A machine of the class described comprising in combination a plurality of character members, feed mechanism comprising a movable carrier provided with stops, a power member, a plurality of setting devices for said stops, provided with means for engaging said power member, a power driven cam, and restoring means for said stops operated thereby.

7. A machine of the class described comprising in combination a plurality of character members, feed mechanism comprising a movable carrier provided with stops, selecting means operated by said character members, power operated stop setting means controlled by said selecting means, and comprising a reciprocating driver, a cam and a follower therefor for operating said driver, and restoring means for said stops likewise operated by said follower.

In testimony whereof I affix my signature in the presence of two witnesses.

JOHN C. BARCLAY.
